UNITED STATES PATENT OFFICE.

THOMAS D. GIGUERE, OF NORTH ATTLEBORO, MASSACHUSETTS.

BRACELET.

No. 843,888.

Specification of Letters Patent.

Patented Feb. 12, 1907.

Application filed October 19, 1906. Serial No. 339,715.

To all whom it may concern:

Be it known that I, THOMAS D. GIGUERE, a citizen of the United States, residing at North Attleboro, in the county of Bristol and State of Massachusetts, have invented a new and useful Improvement in Bracelets, of which the following is a specification.

This invention has reference to an improvement in bracelets, and more particularly to an improvement in expandible bracelets composed of a plurality of spring-actuated units.

The object of my invention is to improve the construction of an expandible bracelet, whereby the spring units forming the bracelet are simplified and strengthened and a more durable and perfect bracelet constructed than has heretofore been done.

A further object of my invention is to reduce the cost of manufacturing expandible bracelets composed of a plurality of spring-actuated units.

My invention consists in the peculiar and novel construction of an expandible bracelet composed of a plurality of spring-actuated units, said units having details of construction, as will be more fully set forth hereinafter and claimed.

Figure 1 is an edge view of an expandible bracelet composed of a plurality of my improved spring-actuated units and showing the bracelet in the contracted or normal position. Fig. 2 is an enlarged detail sectional view of two units, taken on line 2 2 of Fig. 1 looking from the face toward the back and showing the position the springs would assume to hold the units in their normal or contracted position. Fig. 3 is an enlarged detail sectional view similar to Fig. 2, showing the units in their expanded position. Fig. 4 is an enlarged sectional view taken on line 4 4 of Fig. 3 through the units in their expanded position. Fig. 5 is a side view of the two-part shell of a unit, showing the slot in the side of the shell for a connecting-link. Fig. 6 is a side view of the box-frame of the unit, showing the opening in the side for a connecting-link. Fig. 7 is a perspective view of a tubular connecting-link. Fig. 8 is a face view of the springs used in a unit, and Fig. 9 is a perspective view of a spring-retaining member used for holding the springs in their operative position in a unit.

In the drawings, Fig. 1 illustrates an expandible bracelet composed of a plurality of

spring-actuated units *a a*, each unit consisting of a double shell *b*, composed of two coinciding members, a box-frame *c*, a tubular connecting-link *d*, two heart-shaped actuating-springs *e e*, and an I-shaped spring-retaining member *f*. Each member of the shell *b* is stamped up from sheet metal to form a rectangular shallow box 10, having the bottom 11, forming either the inner or outer face of the bracelet, the ends 12 12, and the sides 13 13, in which are the oppositely-disposed openings 14 14, extending in from the edge and forming when the members are brought together the elongated slots 15 15 for the connecting-links *d d*, as shown in Fig. 5. The box-frame is stamped up from sheet metal to form a rectangular box having the flat bottom 16, the double semicircular-shaped ends 17 17, and the sides 18 18, in which are the oppositely-disposed openings 19 19, extending in from the edge for the connecting-links *d d*, as shown in Fig. 6, and coinciding with the slots 15 15 in the shell *b*.

The tubular connecting-links *d d* are each in the form of a flattened tube having the flat faces 20 20, the closed ends 21 21, and the open sides 22 22, as shown in Fig. 7. The thickness and width of the links coincide with the slots 15 15 in the shells *b b*. The actuating-springs *e e* are each constructed from spring-wire bent in the shape of an elongated heart to form the closed end 23, shaped to fit in the ends 17 17 of the box-frame *c* and the spring-arms 24 24, as shown in Fig. 8. The I-shaped spring-retaining member *f* is formed from sheet metal and shaped to have the thin stem 25 merging into the T-shaped ends 26 26, as shown in Fig. 9.

In assembling the units to form a bracelet the spring-arms 24 24 of the springs *e e* are inserted into the connecting-links *d d* through the open sides 22 22 in a position for the arms to straddle the adjacent closed ends of two links to overlap each other in the links and bear on the ends of the links, as shown in Fig. 2. The springs with the links are now placed in a box-frame *c* in a position for the closed ends 23 23 of the springs to enter the ends 17 17 of the frame and for the links to extend outward through the openings 19 19 in the frame, the spring-retaining member *f* placed in the box-frame intermediate the links with the T-shape ends 26 26 against the closed ends 23 23 of the springs, as shown in Fig. 3.

and the frame *c* inclosed in the two-part shell *b* in a position for the links *d d* to extend outward through the slots 15 15 in the sides of the shell. The two parts of the shell *b* are now 5 secured to the frame *c* by solder or other means. These operations are repeated as many times as there are units in the bracelet. The bracelet can now be expanded by pulling the units apart against the tension of the 10 spring-arms 24 24, which engaging with the sides 18 18 of the frame *c* limits the expansion of the units, as shown in Fig. 3. When released, the units assume their normal or contracted position, as shown in Figs. 1 and 2, 15 through the tension of the spring-arms 24 24.

It is evident that the shell *b* of the unit could be shaped to conform to the contour of the box-frame *c* or have any design or configuration desired without materially affecting the 20 spirit of my invention.

Having thus described my invention, I claim as new and desire to secure by Letters Patent—

1. In a bracelet, a plurality of units having 25 connecting-links, and springs in the units straddling the adjacent ends of the connecting-links, whereby the units are held in their contracted or normal position under spring tension.

30 2. A bracelet composed of a plurality of units consisting of a shell, a frame in the shell, connecting-links extending through slots in the frame and shell, and springs in the frame straddling the adjacent ends of the connecting-links, whereby the units are held in their normal or contracted position under spring tension.

35 3. A bracelet composed of a plurality of units consisting of a shell, a frame in the shell, tubular connecting-links extending through openings in the frame and shell, springs in the frame straddling the adjacent ends of the connecting-links, and means for holding the springs in their operative positions in the 40

frame, whereby the units are held in their 45 normal or contracted position under spring tension.

4. A bracelet composed of a plurality of 50 spring-actuated units consisting of a shell, a frame in the shell, tubular connecting-links 55 extending through openings in the shell and frame, springs in the frame having spring-arms straddling the adjacent ends of the connecting-links, whereby the units are held in their normal or contracted position under 55 spring tension, and means for limiting the expansion movement of the units, consisting of the spring-arms engaging with the sides of the frame, as described.

5. A bracelet comprising a plurality of 60 spring-actuated units consisting of a shell, a frame in the shell, tubular connecting-links extending through openings in the shell and frame, wire springs in the frame having 65 spring-arms straddling the adjacent ends of the connecting-links in the frame, means for holding the springs in their operative positions 70 in the frames, whereby the units are held in their normal or contracted position under spring tension, and means for limiting the expansion or opening movement of the units, as described.

6. A bracelet comprising a plurality of 75 spring-actuated units *a a*, each unit consisting of a double shell *b*, a box-frame *c*, a tubular connecting-link *d*, two heart-shaped wire springs *e e* in the frame straddling the adjacent ends of the connecting-links, and a spring-retaining-member *f*, as shown and described.

In testimony whereof I have signed my name to this specification in the presence of two subscribing witnesses.

THOMAS D. GIGUERE.
